BEACON

Erik Robert Parsberg, Lidingo, Sweden, assignor to American Gas Accumulator Company, Elizabeth, N. J., a corporation of New Jersey

Application October 17, 1938, Serial No. 235,324
In Sweden October 31, 1936

4 Claims. (Cl. 177—352)

This application is a continuation-in-part of my copending application Serial No. 170,046, for Beacons, filed in the United States on October 20, 1937, and in Sweden on October 31, 1936, and relates back thereto for all common subject matter.

My invention relates to aerial beacons, that is, to beacons for guiding aircraft.

One of the objects of my invention is to provide a beacon of this nature which indicates to the pilot of the aircraft the direction of the proper flying route, and also makes it possible for the pilot to identify the particular beacon which he is observing. Another object of my invention is to provide a beacon having the foregoing characteristics and in which the beam of light emitted therefrom is projected above a horizontal plane during all, or at least a major portion of the time.

Heretofore, beacons have been provided in which the beam of light is caused to rotate about a vertical axis, the beam either being projected in a substantially horizontal direction, or in an upwardly inclined direction so as to describe a cone. With a beacon of this nature, while the beam is always at or above a horizontal plane, and therefore visible to a pilot, the beacon gives no indication as to direction, inasmuch as it rotates continuously through 360°. Consequently, a pilot approaching the beacon has no way of determining his actual direction of flight. There have also been provided beacons in which the light source rotates continuously about a horizontal axis. While such a beacon enables a pilot to determine his direction of flight, providing he knows the orientation of that particular beacon, the beam emitted thereby is directed into the ground during one-half the revolution and is therefore of no utility.

Further objects and advantages of my invention will be apparent from the following description considered with the accompanying drawings which form part of this specification and of which:

Fig. 1 illustrates diagrammatically a method of signaling in accordance with one embodiment of my invention;

Fig. 2 is a side view of an apparatus for producing signals in accordance with the method illustrated in Fig. 1;

Fig. 3 is a cross-sectional view taken on the line 3—3 of Fig. 2;

Fig. 4 is a perspective view of the light source shown in Figs. 2 and 3;

Fig. 5 is a perspective view of a modified form of light source;

Fig. 6 illustrates diagrammatically a method of signaling in accordance with another embodiment of my invention;

Fig. 7 is an end view of an apparatus for emitting signals in accordance with the method illustrated in Fig. 6;

Fig. 8 illustrates diagrammatically a method of signaling in accordance with a third embodiment of my invention;

Fig. 9 is an end view of an apparatus for producing signals in accordance with the method shown in Fig. 8;

Fig. 10 illustrates diagrammatically a still further method of producing signals;

Fig. 11 is a side view of an apparatus for producing the signals shown diagrammatically in Fig. 10;

Fig. 12 is a cross-sectional view taken on the line 12—12 of Fig. 11;

Fig. 13 is a cross-sectional view taken on the line 13—13 of Fig. 11;

Fig. 14 illustrates diagrammatically another method of producing signals;

Fig. 15 is a side view of an apparatus for producing signals shown in Fig. 14;

Fig. 16 is an end view of the apparatus shown in Fig. 15;

Fig. 17 is a cross-sectional view taken on the line 17—17 of Fig. 15;

Fig. 18 is a side view of an apparatus for producing signals in accordance with a further embodiment of my invention; and

Fig. 19 is a cross-sectional view taken on the line 19—19 of Fig. 18.

Referring more particularly to Fig. 1, reference character 10 designates generally a light source adapted to be rotated about an axis 11.

As indicated by the arrows, the light source is rotated through 180° so that the beam 12 emitted thereby passes from a horizontal position upwardly to a vertical position and thence downwardly to a horizontal position. The rotation of

the light source is then reversed. Consequently, the beam is always directed along or above a horizontal plane, and is never directed into the ground. The beam is thus at all times available as a beacon. Moreover, the axis 11 is arranged at right angles to the flying route at the point where the beacon is placed and thus the symmetric axis 13 of the beam sweeps back and forth along the route and clearly indicates its direction to a pilot.

In Figs. 2 and 3 there is shown an apparatus

for producing the above described signals. Reference character 14 indicates a casing within which may be mounted any suitable source of power, such as an electric motor arranged to drive a cam disk 15 at constant speed. Disk 15 is provided with a cam track 16 of the shape shown in Fig. 3. A member 17 is pivotally mounted on a shaft 18 carried by a fixed arm 19. One end of member 17 is provided with a cam follower 20, while the other end is in the form of a segment 21 of a gear. The teeth of this segment mesh with a pinion 22 mounted on a shaft 23 which also carries a reflector 24. Mounted at or parallel to the axis of rotation of reflector 24 is an elongated light source, such as a tubular high pressure mercury lamp 25. An additional reflector 26 may be placed in front of the lamp so as to reflect the light which strikes it back against the main reflector 24. This arrangement of reflectors and elongated light source will emit a flat fan-shaped beam 12, as shown in Fig. 1.

The operation of the above described device is as follows: As cam disk 15 rotates at a constant speed in the direction of the arrow shown in Fig. 3, the cam track 16 causes the follower 20 to move toward and away from the center of rotation of the cam. This causes the member 17 to rock back and forth on the shaft 18 through a certain angle. The gear ratio between gear segment 21 and pinion 22 is such that this rocking movement causes the pinion 22 and the shaft 23 to oscillate through 180°. The reflector 24 is so arranged on the shaft 23 that the beam emitted thereby swings back and forth through 180°, but always at or above a horizontal plane.

Instead of the reflector arrangement illustrated in Fig. 4, a Fresnel type lens 27 may be employed with a reflector 28 and the elongated light source 25 in order to produce a beam in the form of a plane fan-shaped cluster. In the embodiments hereinafter described, either of the light sources illustrated in Fig. 4 or 5 may be employed.

In Fig. 6 there is shown diagrammatically a form of signal wherein the beam is caused to rotate through approximately 180°, then reverse its direction and rotate through a smaller angle α , reverse again through the angle α , and reverse a third time and travel through 180°. This reversing of the movement of the beam near the horizon is a characteristic of a particular beacon, thus enabling a pilot to identify the beacon and, knowing the location of this particular beacon, he is able to determine his own location.

The apparatus shown in Figs. 2 and 3 may be modified to produce the signals shown in Fig. 6 by substituting the cam disk 30 shown in Fig. 7. The cam track 31 is formed with reverse curves 32 and 33. That is, at the point where the track 31 is approaching the greatest distance from the center of rotation of the cam disk, the track is caused to curve in slightly toward the center, as shown in 32, while at the point where the track is approaching closest to the center, it is caused to curve out slightly therefrom.

The above described device operates as follows: As the disk 30 rotates in the direction of the arrow from the position shown in Fig. 7 the cam follower 20 is caused to move toward the left, thus rotating member 17 in a clockwise direction. This movement continues until the reflector 24 has been rotated in a clockwise direction far enough to cause the beam emitted

thereby to extend substantially horizontal. At this point, the first half of the portion 33 of the cam track causes the follower 20 to be moved a short distance to the right, thus rotating the member 17 in a counterclockwise direction sufficient to rotate the reflector 24 in a clockwise direction through the angle α . As the disk continues to rotate, the second half of the portion 33 causes the follower to again move to the left, thus rotating the member 17 in a clockwise direction and the reflector 24 in a counterclockwise direction back through the angle α . Thereafter, further rotation of the cam disk causes the follower 20 to move to the right as it travels in the track from the portion 33 to the portion 32, this part of the track being designed to rotate the member 17 in a counterclockwise direction through a sufficient angle to cause the reflector 24 to rotate 180° in a clockwise direction. The portion 32 of the cam track acts similar to the portion 33, that is, it causes an oscillation of the reflector through the angle α , before the reflector is caused to turn back through 180°.

The signal as illustrated in Fig. 8 consists in rotating the beam through an angle equal to $90^\circ + \frac{1}{2}\beta$, then reversing the beam through the angle β , and then causing it to continue to rotate through an angle of $90^\circ + \frac{1}{2}\beta$. In other words, the beam rotates from the horizon to a little past the zenith, then turns back through a small angle, and then reverses and continues to the other horizon.

The cam arrangement suitable for producing such motion is shown in Fig. 9. The cam disk 35 is provided with a track 36 having portions 37 and 38 which produce the oscillation of the beam through the angle β when the beam is near the zenith, in a manner similar to that described in connection with Fig. 7.

In the signal diagrammatically shown in Fig. 10, the beam is caused to rotate about the axis 11 of the light source through 180°, whereupon rotation about this axis is interrupted, while the beam is caused to oscillate back and forth through 180° about the symmetric axis 13. An apparatus suitable for producing such a beam is shown in Figs. 11, 12 and 13. In this apparatus a shaft 40 is driven at a constant speed by means of any suitable motor in the housing 14. Shaft 40 carries a cam disk 41 having a cam track 42 on one side thereof and a cam track 43 on the other side thereof. Pivotally mounted on a fixed shaft 44 is a member 45, one end of which carries a cam follower 46 which cooperates with the cam track 42. The other end of member 45 is formed as a gear segment 47 which meshes with a pinion 48 mounted on a tubular shaft 49 carried in suitable bearings. The opposite end of tubular shaft 49 is enlarged to form a gear box 50 and provides a bearing 51 in which is mounted a shaft 52 to the outer end of which is rigidly secured reflector 24.

The inner end of shaft 52 carries a bevel gear 53 meshing with a similar gear 54 which is mounted on the end of a shaft 55, the shaft extending within and beyond the tubular shaft 49. The opposite end of shaft 55 carries a pinion 56 which meshes with a gear segment 57 formed on a member 58 which is pivoted on a shaft 59. The opposite end of member 58 carries follower 60 which cooperates with the cam track 43.

The above described apparatus operates as follows. It will be seen that rotation of the hollow shaft 49 causes the reflector 24 to rotate about an axis coinciding with the center of the shaft,

which axis is parallel and close to the axis 11 through the light source. Rotation of the shaft 55, on the other hand, causes shaft 52 to rotate, thus causing the reflector 24 to rotate about the symmetric axis 13 of the beam. Rotation of the hollow shaft 49 is caused by oscillating movement of the member 45, which results from the cam follower 46 being moved back and forth as the cam track 42 approaches towards and recedes from the center of rotation of the cam. Rotation of the inner shaft 55 results from oscillation of the member 58 caused by the cooperation of the follower 60 with the cam track 43. Cam track 42 is formed with two concentric portions 61 and 62 so that, while the follower is within these concentric portions, no movement of the member 45 results. Likewise cam track 43 is formed with two concentric portions 63 and 64. The concentric portions of the two cams are so arranged with respect to each other that, when the follower 46 is in either the concentric portion 61 or 62, the follower 60 will be in an eccentric portion of the cam tracks 43. Likewise, when the follower 60 is within the concentric portion 63 or 64, the follower 46 will be in an eccentric portion of the track 42. Hence, rotation of shafts 49 and 55 do not take place at the same time, one shaft being held stationary while the other turns and vice versa.

The above mechanism produces the signal shown in Fig. 10. As the beam is caused to rotate through 180° about the axis 11 by means of the member 45 rotating the hollow shaft 49, the inner shaft 55 is held stationary, as follower 60 is in one of the concentric portions 63 or 64 of track 43. When the beam reaches a substantially horizontal plane, the hollow shaft 49 is held stationary, as follower 46 is in one of the concentric portions 61 or 62 of track 42, while the inner shaft 55 is rotated 180° in one direction and then 180° in the reverse direction by the cooperation of follower 60 with an eccentric portion of cam track 43.

The above described movements of the beam result in different signals, depending upon whether the pilot is flying along the correct route, or off to one side of the same. When following the route at approximately the same elevation as the beacon and hence approaching the beacon along an extension of the symmetric axis 13, the pilot will see the signal brightly while the reflector is not rotating about the axis 11, that is while it is rotating about the axis 13. Due to the fact that he is in direct line with this axis, the rotation about the axis 13 will not be apparent to him, as he will receive the direct rays of the light throughout the entire period of rotation. Consequently, he will see flashes of long duration spaced at comparatively long intervals, the intervals being the time required for the beam to rotate about the axis 11 to the opposite horizon, oscillate about the axis 13, and return to the horizon from which the ship is approaching.

If the pilot is approaching the beacon at the same elevation but from an angle, or flying parallel to the route but a substantial distance to either side thereof, the signal will appear to him as three flashes, a long interval, three flashes, etc. This is caused by the fact that, as the fan-shaped beam comes down to the horizon, the edge of the beam strikes the pilot and gives him one flash. Almost immediately, the beam starts to rotate about the axis 13, and the pilot is no longer within the direct rays of the edge of the

beam. However, when the beam has rotated 180° around the axis 13, the opposite edge thereof strikes the pilot, giving him a second flash which is terminated when the beam starts to rotate back through 180° around the axis 13. The third flash is received when the first edge of the beam again strikes the pilot. He thus knows that he is off to one side of the proper route, and may correct his course accordingly.

However, if the pilot is flying a substantial distance above the plane of the beam when the latter is in a substantially horizontal position, he observes four flashes, of which the two middle ones will be of longer duration; the closer to the proper route the pilot is flying. Moreover, the lower the flying height, the shorter is the interval between the two middle flashes if the ship is off to one side of the beacon, or between the first and second flashes and between the third and fourth if the ship is off to the other side of the beacon.

The four flashes are caused as follows, assuming that the beam rotates about the axis 13 first in a clockwise direction and then in a counterclockwise direction, and assuming that the ship is above and to the right of the axis 13. As the beam comes down toward the horizon, one edge thereof passes the pilot and he observes one flash which is of the same duration, regardless of the distance the ship is above or to the right of the axis. As the beam turns over around the axis 13 he receives another flash. The interval between these two flashes depends upon his distance to the right and above the axis. The further he is above the axis, the shorter will be the interval, due to the fact that the beam rotates through a smaller angle before it strikes him. Likewise, the closer he is to the axis in a horizontal direction, the smaller will be this angle and hence the shorter the interval. Moreover, the closer he is to the axis, the longer will be the duration of the second flash, inasmuch as the linear velocity of the beam is less close to its axis of rotation and hence it does not pass the pilot so rapidly. The third flash is received when the beam rotates back around the axis 13. The closer the ship is to the ground, the shorter will be the interval between the second and third flashes, due to the fact that the beam is required to turn through a smaller angle. Also the further the ship is to the right of the axis, the shorter will be the interval for the same reason. The duration of the third flash for any given position of the ship will be the same as the duration of the second flash, that is the duration will be longer the closer the ship is to the axis 13. The fourth flash is obtained when the beam again rotates about the axis 11 back toward the other horizon. For a given position of the ship, the interval between the third and fourth flashes will be the same as between the first and second.

If the ship is to the left of the axis 13, the duration of the various flashes will be the same as though the ship were a similar distance to the right of the axis, but the intervals between the flashes will be different. The first flash is received when the beam, rotating about the axis 11, passes the pilot on its way down to the horizon. The second flash will be received when the beam rotates in a clockwise direction about the axis 13. Due to the fact that the beam rotates less than 90° about the axis 13, before striking the ship when the latter is to the left of the axis, whereas the beam must rotate more

than 90° when the ship is to the right of the axis, the interval between the first and second flashes will be shorter when the ship is to the left than when it is to the right. The third flash is received when the beam rotates counterclockwise about the axis 13. The interval between the second and third flashes is the time required for the beam to rotate about the axis 13 more than 90° until it reaches a horizontal position and then rotates back through more than 90° until it again strikes the ship on the left side of the axis 13. This results in a comparatively long interval between the second and third flashes when the ship is to the left of the axis, whereas, as above explained, the interval between the second and third flashes is short when the ship is to the right of the axis. The fourth flash is observed when the beam rotates back about the axis 11 and the interval between the third and fourth flashes is the same as between the first and second.

Thus, the pilot is able to determine, by observing the intervals between the flashes, and the duration of the second and third flash, how far and to which side he is off the proper flying route, and thus is enabled to alter his course accordingly.

It will be noted that the same beacon may appear to a pilot to emit different signals, depending on whether the pilot is approaching it at the elevation of the beacon, under which condition he receives three flashes, or approaching it at a higher elevation, under which condition he receives four flashes. This would tend to confuse the pilot as to the identity of the beacon. Consequently, if the beacon is so located that it is possible for the pilot to approach it at the same elevation, for instance if the beacon is on a mountain top, it is preferable to rotate the beam more than 180° around the axis 11 so that the symmetric axis 13 is inclined downwardly during the time that the beam rotates therearound. If this is done, the pilot obtains four flashes, even though he is flying in the same horizontal plane as that occupied by the beacon.

The signal illustrated in Fig. 14 consists in oscillating a beam back and forth from one horizon to the other about the axis 11, while at the same time causing it to continuously oscillate rapidly through a small angle δ , about its symmetric axis 13. The apparatus shown in Figs. 15, 16 and 17, produces such a signal. This apparatus consists of a cam disk 70 provided with a cam track 71, which is of the same contour as the cam track 16 shown in Fig. 3. Thus, the shaft 72, driven by the pinion 73 meshing with the gear segment 74 is caused to oscillate through 180° . The reflector 24 is pivotally mounted on a pin 75 extending at right angles to the axis of rotation of shaft 72 and thus the reflector is caused to oscillate through 180° .

Secured to the reflector adjacent to one end thereof is a pair of arms 76 and 77 which carry rollers 78 and 79. A gear 80 is rigidly mounted on an arm 81 and the rollers 78 and 79 are caused to travel around the teeth of gear 80. The length of the arms 76 and 77 is so proportioned that, when the roller 78 is between two teeth, the roller 79 is at the outer end of a tooth. Thus, as the reflector is rotated about the center of the shaft 72, the rollers 78 and 79 are caused to travel about the periphery of gear 80, but in order to be able to do so, they cause the reflector to oscillate about the pin 75 as one roller moves out of the space between two teeth and the other

roller moves into the space between teeth on the opposite side of the gear 80. This causes the beam to oscillate or vibrate through the angle δ , while it is being rotated back and forth through an angle 180° about the axis 11.

Thus as long as the pilot is flying the correct route, which coincides with the axis 13, he will observe the beam as a steady flash of light as it sweeps across him during its travel back and forth about the axis 11. However, if he is off to one side of the correct route, he will be struck by the edge of the flat beam and, inasmuch as the edge of the beam is continuously vibrating through the angle δ , the beam will appear to flicker as it passes him. Moreover, the further he is off the correct course the more apparent will be the flicker, inasmuch as the further away from the axis 13, the greater will be the linear movement of the edge of the beam which results from its oscillation through the angle δ .

In Figs. 18 and 19 there is illustrated an apparatus for producing a beam which rotates in a constant direction, but which is above the horizon a greater percentage of the time than it is below. Mounted on the shaft 85, which is driven at a constant speed, is an elliptical gear 86 which meshes with a similar elliptical gear 87 which is mounted for rotation on a fixed shaft 88 and is fixed to a circular gear 89. Gear 89 meshes with pinion 90, having one-half the number of teeth of the gear 89, whereby a gear ratio of two to one is obtained. Pinion 90 is mounted on a shaft 91 which carries the reflector 24.

The above described device operates as follows. Rotation of the shaft 85 and the elliptical gear 86 at a constant speed causes the elliptical gear 87 to be driven at a varying speed. In the position of the elliptical gears shown in Figs. 18 and 19, that is with the major axis of the gear 86 cooperating with the minor axis of the gear 87, the effect is that of a large gear driving a small gear, and therefore at this instant the gear 87 rotates at a higher speed than the gear 86. However, when the gear 86 has turned through 90° , its minor axis cooperates with the major axis of the gear 87, and the effect is that of a small gear driving a large gear and hence the gear 87 at this instant rotates at a slower speed than the gear 86. Between these two positions of the axes of the elliptical gears, the speed is continuously varying. It will thus be seen that for each revolution of the gear 87, it first travels faster than the gear 86, then slower, then faster again, and then slower. However, it is desired that the reflector 24 travel slowly through one-half of each revolution and rapidly through the other half. This is accomplished by providing a two to one gear ratio between the elliptical gear 87 and the shaft 91. The gears are so arranged that the reflector 24 travels slowly during that half of its revolution in which the beam is above the horizon and travels rapidly during the other half of its revolution when the beam is below the horizon and useless as a signal.

While I have shown several more or less specific embodiments of my invention, it is to be understood that this has been done for purposes of illustration only and that the scope of my invention is not to be limited thereby, but is to be determined by the appended claims when construed in the light of the prior art.

What I claim is:

1. A beacon for signalling to aircraft, comprising light producing means, elongated projecting

means adapted to produce a wide and relatively thin and flat beam of light, means for mounting said projecting means for rotation about a substantially horizontal axis of rotation substantially parallel to the longitudinal axis of said projecting means, means for repeatedly rotating said projecting means back and forth within an angular path about said axis of rotation, and means for regulating said rotation so that said projecting means may project said beam above the horizontal plane of said axis for a longer period of time than below said plane.

2. A beacon for signalling to aircraft, comprising light producing means, elongated projecting means adapted to produce a wide and relatively thin and flat beam of light, means for mounting said projecting means for rotation about an axis parallel to the length of said projecting means, means for repeatedly rotating said projecting means back and forth within an angular path about said axis, and means for regulating said rotation so that at least a portion of said path is above the horizontal plane extending through said axis.

3. A beacon for signalling to aircraft, comprising light producing means, elongated projecting means adapted to produce a wide and relatively thin and flat beam of light, means for mounting

said projecting means for rotation about an axis parallel to the length of said projecting means, means for repeatedly rotating said projecting means back and forth through approximately 5 180° within an angular path about said axis, means for alternately rotating said projecting means back and forth through less than 180° within said path, and means for regulating said rotation so that at least a portion of said path is above the horizontal plane extending through said axis.

4. A beacon for signalling to aircraft at high altitudes, comprising light producing means, elongated projecting means adapted to produce 15 a wide and relatively thin and flat fan-shaped beam of light, means for mounting said projecting means for rotation about a first horizontal axis substantially parallel to the length of said projecting means and about a second axis normal to said first axis, means for repeatedly rotating said projecting means back and forth in an angular path about said first axis, means for alternately rotating said projecting means about said second axis, and means for regulating said 20 rotation so that at least a portion of said path may be maintained above the horizontal plane extending through said first axis.

ERIK ROBERT PARSBERG.
